(57) **CLAIM**

The ornamental design for a bottle, as shown and described.

DESCRIPTION

FIG. 1 is a perspective view of a bottle showing my new design.

FIG. 2 is a front view of the bottle shown in FIG. 1, the rear view being a mirror image thereof.

FIG. 3 is a right side view of the bottle shown in FIG. 1, the left side view being a mirror image thereof.

FIG. 4 is a top view of the bottle shown in FIG. 1; and, FIG. 5 is a bottom view of the bottle shown in FIG. 1.

The broken lines shown in FIGS. 1 through 4 are for illustrative purposes only and form no part of the claimed design.

The oblique line shading shown on the drawings represents reflective surfaces.
